UNITED STATES PATENT OFFICE.

FRANK Q. DUTTON, OF PHILADELPHIA, PENNSYLVANIA, ASSIGNOR OF ONE-THIRD TO
EMANUEL G. KOLB, OF PHILADELPHIA, PENNSYLVANIA.

TELEPHONE.

1,125,823.

Specification of Letters Patent.

Patented Jan. 19, 1915.

Application filed March 22, 1912. Serial No. 635,443.

To all whom it may concern:

Be it known that I, FRANK Q. DUTTON, a citizen of the United States, and a resident of Philadelphia, county of Philadelphia, and State of Pennsylvania, have invented certain new and useful Improvements in Telephones, of which the following is a specification, reference being had to the accompanying illustrations.

10 This invention particularly relates to a silencer for telephones, the principal object of which is to prevent the transmission of sounds not intended to be directed to the party listening at the opposite end of the 15 telephone line.

Other objects of this invention are, to provide a medium upon which advertising matter may be cheaply and conspicuously displayed, and to form such advertising medium with a portion substantially conforming to the mouthpiece of the transmitter, and having a suitable surface for receiving the advertising matter, and a resilient portion for muffling the transmitter, by frictionally engaging the walls of the mouth-piece.

It is common practice for one speaking over a telephone to divert his conversation, particularly by way of questions, to a person in close proximity to the local telephone set, and at the same time to muffle the transmitter by placing his hand over the mouthpiece, to prevent the party at the other end of the telephone line from hearing the local 30 conversation. It often happens, however, that the party using the instrument desires to carry on a conversation in the same room in which the telephone set is located, or an adjoining room, and at the same time to be 35 himself reviewing records or other data at such a distance from the telephone set as would preclude his silencing the transmitter.

It will be obvious that the device herein contemplated may be conveniently employed 40 under such circumstances to silence the transmitter, and thereby permit the speaker to leave the telephone without fear of his private conversation being transmitted over the wire to the listening party at the other 45 end of the telephone line.

This invention further comprehends all of the various novel features of construction and arrangement hereinafter more definitely specified.

50 The silencing device may be best under-

stood from the accompanying illustrations, in which—

Figure 1 represents a perspective view of a telephone set showing the receiver detached from the switch-hook, and a silencer 60 conveniently constructed in accordance with this invention, co-operatively engaged in the mouthpiece of the transmitter, to prevent the transmission of sounds thereby; Fig. 2 is a perspective view of the silencer *per se*; 65 and Fig. 3 is a perspective view of a modified form of silencer.

In said figures, the telephone set comprises the stand 5, switch-hook 6, transmitter 7 mounted to rock on the pivot 8, and having 70 the mouthpiece 10 and the receiver 11, which, being removed from the switch-hook 6, indicates that the telephone set is in operative connection with a complementary telephone set at the other end of a 75 telephone line.

The silencer 12 is shown in operative position within the mouthpiece 10 of the transmitter 7, and comprises the tapering body portion 14, preferably formed of a 80 solid material, such as wood, and substantially conforming to the contour of said mouthpiece, and the resilient tip 15, preferably formed of a resilient material, such as cork, rubber, etc., secured to the free tapered end of the body 14, and arranged to be forced into said mouthpiece and to support the silencer by its frictional engagement with the walls thereof.

As best shown in Fig. 1, the silencer may 90 be conveniently supported upon the instrument, when not in use, by a flexible cord 16 conveniently attached to the silencer body 14 by the retaining tack or screw 17, and having its free end looped over the mouthpiece 10 of the transmitter 7 and suspended therefrom, as shown in dotted lines in Fig. 1.

As best shown in Fig. 2, the silencer body 14 is provided at its larger end with a 100 rim 20 surrounding a substantially flat surface 21, upon which advertising matter 22 may be applied, either by impressing or printing directly upon said surface, or by pasting printed labels thereon.

Although the silencer as shown in Fig. 1 relies principally upon its frictionally engaged smaller end, it is obvious that its larger end may as readily obstruct the 105 ori-

ifice of the mouthpiece.

In the modification shown in Fig. 3, the silencer 25 is provided with spring clips 26, which may be conveniently engaged with the peripheral margin of the mouthpiece 5 to hold said silencer in position to obstruct the orifice of said mouthpiece.

It will be obvious that by constructing the silencer in the manner above described, such advertising matter as may be placed thereon will be conspicuous in either its operative or inoperative position, and that the natural tendency when using the telephone set will be to pick up the silencer to ascertain its purpose, and read the advertisement thereon.

It is not desired to limit this invention to the precise details of construction and arrangement herein set forth, as it is obvious that various modifications may be made 20 therein without departing from the essential features of the invention as defined in the appended claims.

Having thus described my invention, I claim:

25 1. A silencer for a telephone, comprising a body portion adapted to enter the mouthpiece of the telephone and to provide suitable space for the display of advertising matter thereon, and a contact portion of 30 resilient material rigidly affixed to said body portion, said contact portion being adapted by contact with the restricted portion thereof to support said silencer therein, the body portion of said silencer being out of contact 35 with said mouthpiece.

2. A silencer for a telephone, comprising a wooden body portion formed to loosely enter the mouthpiece of the telephone, one end of said body portion being adapted for the display of advertising matter, and a contact portion formed of cork rigidly affixed upon the other end of said body portion and operative to support said silencer within said mouthpiece by frictional engagement 40 with the interior thereof, the body portion of said silencer being out of contact with said mouthpiece.

3. A silencer for a telephone, comprising a wooden body portion having a contour 50 somewhat similar to the contour of the interior of the mouthpiece of a telephone and adapted to enter therein, one end of said body portion presenting an enlarged surface for the display of advertising matter, 55 a substantially cylindrical contact portion formed of cork rigidly affixed upon the other end of said body portion and operative to support said silencer within said mouthpiece by frictional engagement of its periphery with the restricted interior portion thereof, the body portion of said silencer being out of contact with the interior of said mouthpiece, and means operative to support 60 said silencer from said mouthpiece when in 65 inoperative position.

In witness whereof, I have hereunto set my hand this 21st day of March, A. D., 1912.

FRANK Q. DUTTON.
